UNITED STATES PATENT OFFICE.

GEORGE HILLIARD VINCENT, OF WELTY, OKLAHOMA.

COTTON-PICKING DEVICE.

1,128,556.

Specification of Letters Patent. Patented Feb. 16, 1915.

Application filed March 11, 1914. Serial No. 823,990.

To all whom it may concern:

Be it known that I, GEORGE H. VINCENT, a citizen of the United States, residing at Welty, in the county of Okfuskee, State of Oklahoma, have invented certain new and useful Improvements in Cotton-Picking Devices; and I do hereby declare the following to be a full, clear, and exact description of the invention, such as will enable others skilled in the art to which it appertains to make and use the same.

This invention relates to cotton picking devices.

The object of the invention resides in the provision of a device of the character named adapted to be worn on the hand and which will facilitate the operation of picking the cotton and in addition protect the hand of the user.

A further object of the invention resides in the provision of a cotton picking device which will be simple in construction, easily applied to and removed from the hands, and which can be manufactured at a comparatively small cost.

With the above and other objects in view the invention consists in the details of construction and in the arrangement and combination, of parts to be hereinafter more fully described and particularly pointed out in the appended claims.

In describing the invention in detail reference will be had to the accompanying drawings wherein like characters of reference denote corresponding parts in the several views, and in which—

Figure 1 is a perspective view showing the device applied to the hand; Fig. 2, a perspective view of the device detached; Fig. 3, a perspective view of one of the clamping elements of the device, and Fig. 4, a plan view of one of the flexible strips of the device before a clamping element is attached thereto.

Referring to the drawings the improved cotton picking device is shown as comprising a flexible wrist band 10 provided with a buckle 11 whereby same may be easily applied to and removed from the wrist.

The device further embodies four finger strips 12 having their inner ends attached to the wrist band 10 and provided respectively with longitudinal openings 13. Secured to the free end of each finger strip 12 is a clamping member A which includes a ring body portion 14 having an extension

15 on one end thereof and said extension being provided on one end with a laterally bent portion 16. Formed on the side of the extension 15 remote from the ring body 14 is a lug 17 having its outer end roughened or serrated as at 18. The ring body 14 is provided with clenching fingers 19 which are engaged through the outer end of a finger strip 12 and then clenched to secure the clamping member to the finger strip as clearly shown in the drawing.

In applying the device the band 10 is first secured to the wrist and the strips 12 carried over the backs of the first three fingers of the hand and the thumb respectively, the ends of the fingers and thumb being engaged through the ring bodies 14 and against the inner sides of respective extensions 15. With the device thus associated with the hands it will be obvious that the cotton can be picked with facility by clamping same between the lug 18 carried by the thumb and the lugs 18 carried by the fingers. It will be further obvious that the openings 13 will permit movement of the thumb and fingers without possibility of rendering the strips 12 taut.

What is claimed is:

1. A cotton picking device comprising a plurality of finger strips each having at one end a finger receiving member provided with a gripping device on what constitutes its inner face in use, each of said strips being slotted adjacent to the finger receiving member in position to receive the second joint of the finger when in use, and means connecting the other ends of the strips and adapted for holding them in position upon the backs of the fingers of an operator with the gripping devices disposed on the inside of the fingers.

2. A cotton picking device comprising a plurality of flexible strips adapted to be positioned along the back of the thumb and fingers, said strips being provided with openings through which the thumb and fingers are adapted to work, rings secured to said strips at one end and engageable over the thumb and fingers respectively, and extensions on the outer ends of said rings positioned to be disposed against and on the inside of the thumb and fingers respectively when the device is in place, and means connecting the other ends of the strips and adapted for holding them in position upon the thumb and fingers of an operator.

3. A device of the class described comprising a wrist band, flexible strips having corresponding ends secured to the wrist band respectively and adapted to be positioned along the rear of the thumb and fingers of a hand, rings secured respectively to the free ends of said strips and engageable over the thumb and fingers, extensions on the outer ends of said rings, and studs on said extensions having serrated outer ends, said

extensions and studs being positioned so as to be disposed on the inside of the thumb and fingers when the device is in place.

In testimony whereof, I affix my signature, in the presence of two witnesses.
